UNITED STATES PATENT OFFICE.

SAMUEL THOMAS WALKUP, OF NEW YORK, N. Y.

FLOWER-PRESS.

1,283,992.

Specification of Letters Patent.

Patented Nov. 5, 1918.

Application filed January 18, 1917. Serial No. 143,013.

To all whom it may concern:

Be it known that I, SAMUEL THOMAS WALKUP, a citizen of the United States of America, residing at 3603 Broadway, city of New York, borough of Manhattan, and State of New York, have invented certain new and useful Improvements in Flower-Presses, of which the following is a specification.

This invention relates to a press for use in the manufacture of artificial leaves of flowers, and more particularly to a press adapted for pressing the blanks of the leaves or flower petals to impress thereon the surface indications characteristic of such leaves or flower petals.

This invention has for an object to provide a press of this nature which will permit of a more rapid operation than heretofore, and which will be of simple and inexpensive construction and in which the manual control movements will be reduced to a minimum.

For further comprehension of the invention, and of the objects and advantages thereof, reference will be had to the following description and accompanying drawings, the various novel features of the invention being more particularly set forth in the appended claims.

Figure 1 of the drawing is a front elevation of a press constructed according to my invention.

Fig. 2 is a sectional elevation at right angles to Fig. 1 of the press proper, the section being taken on the line 2—2 of Fig. 1.

Fig. 3 is a plan view.

Fig. 4 is a face view of a die containing a leaf impression.

Fig. 5 is a side elevation of the two dies in position one upon the other.

Fig. 6 is a horizontal section on the line 6—6 of Fig. 1.

In the embodiment of the invention here illustrated, my improved press comprises an arched frame 1 projecting upwardly from a base 2 and which is preferably mounted on a suitable work table or bench 3.

Mounted on the head 4 of the arched frame, is a vertical guide 5 which extends through a vertical slot 6 in the head and which may be rigidly secured in place by suitable means as the bracket 7. Slidably held in the guide 5, is a plunger bar 8, which may be of T form in cross section and provided on one face with a rack 9 with which a pinion, 10, meshes. This bar has fixed

upon its lower end a presser head 11 adapted to engage the dies as will be pointed out later.

The pinion 10 is connected to a suitable source of motive power here shown as an electric motor 12 mounted on the head 4. I prefer to drive the rack bar 8 at reduced speed from the motor which may have on its armature shaft a pinion 13, meshing with a gear 14, fixed on one end of a short shaft 15, on the opposite end of which the pinion 10 is fixed, this shaft 15 being suitably supported as by the bracket 16, on the head 4. The bar 8 is preferably normally held in its raised position by suitable means, such as the counterweight 17 secured on one end of a rope 18, which passes over the overhead pulleys 19 and 20 and is fastened at its opposite end as at 21 to the upper end of the bar 8.

In order to cause the motor to stop automatically when the presser head has engaged the dies with the requisite pressure, I have provided means for cutting off the electric current to the motor when the head has descended a sufficient distance. As here shown, a vertically disposed rack arm 25 is pivoted midway of its length as at 26 to the guide 5 and carries at its opposite ends a pair of lateral cam projections 27 and 28, which are adapted to be engaged by a stud 29 on the side of the bar 4 to rock the arm. The lower end of this arm carries an insulated contact member 30, adapted to contact with a second contact member 31 on an insulating block 32 fixed to the guide 5, the supply circuit to the motor being through these contact members as will be pointed out later.

The dies here used are detachable and of usual construction, and comprise male and female members 34 and 35 having the usual impression surfaces 36 and 37, a face view of the impression surface of the male die being given in Fig. 4, the female die having a complementary surface, as is well understood, and being provided with a handle, 38, while the male die has an angular flange 34 fitting over female die as shown in Fig. 5, which view shows the dies ready to be inserted under the head. To facilitate the proper positioning of the dies under the head, I provide a V shaped stop member 39 on the base 2 against which the dies are placed and which serves to localize the dies under the head as the latter are pushed in

under the head from the front of the machine by the operator.

To increase the rapidity of operation of the press, I prefer to provide means adapted to cause the motor to start by the positioning of the dies against the above-mentioned stop member. To this end a pair of contact springs 40 and 41 are mounted on an insulating block 42 immediately above the apex 10 of the stop member; the contact spring 41 carrying an insulated button 43 against which the die presses when moved into position, closing the circuit between said contact springs.

15 The electric circuit comprises a wire 45 leading from the source of power to one terminal of the motor, a wire 46 from the other terminal of the motor to the contact 30, a wire 47 from the contact 31 to the spring 20 contact 40 and a wire 48 from the latter to the source of power.

In the operation of the press the leaf or petal to be pressed is placed in the usual manner in the dies, between the surfaces 25 36 and 37 and the latter pushed under the head on the supporting base 2. When the dies engage the V shaped stop the contacts 41 and 42 are connected as shown in Fig. 6 and the motor starts causing the head to descend and raising the weight. When the stud 29 engages the cam 28 on the rack, arm 25 and the contacts 30 and 31 are separated, breaking the circuit and causing the motor to stop; the weight immediately raising the head. If desired a one way clutch connection of any well known type may be connected to the pinion 10 on the short shaft 15 to allow the pinion to run freely backward. When the head nears its uppermost 40 position the stud 29 engages the cam 27 on the upper end of the rock arm 25 and causes contacts 30 and 31 to reengage.

In the meantime the operator will have removed the dies, permitting the contacts 40 45 and 41 to separate and breaking the circuit at this point, preventing starting of the motor again until the dies are again placed in position.

It will be apparent that various changes 50 and modifications might be made in the construction shown without departing from the spirit of the invention and the right is therefore reserved to all changes and modifications as come within the scope of the appended claims.

What I claim is:—

1. In an artificial flower press, a die support and a presser head, an electric motor for moving said head toward said support, 60 electrical connections whereby a closed circuit through said motor may be formed, said electrical connections including a pair of contact members, one of which is movable, and a part adapted to move with the 65 presser head and engage said movable con-

tact member and open the circuit through the motor when the presser head has reached a certain point in its travel.

2. In an artificial flower press, a die support and a presser head, an electric motor 70 for moving said head toward said support, electrical connections whereby a closed circuit through said motor may be formed, said electrical connections including a pair of contact members one of which is movable, a 75 part adapted to move with the presser head and engage said movable contact member and open the circuit through the motor when the presser head has reached a certain point 80 in its travel.

3. In an artificial flower press, a die support and a presser head, an electric motor for moving said head toward said support, independent means for returning said head to its starting point, electrical connections 85 whereby a closed circuit through said motor may be formed, said electrical connections including a pair of contact members one of which is movable, a rocker arm having said movable contact member mounted thereon, 90 and a part carried by the presser head and adapted to engage said rocker arm to ultimately open and close the circuit as the presser head is moved in opposite directions.

4. In an artificial flower press, a die support and a presser head, an electric motor for moving said head toward said support, means for automatically opening the circuit through the motor when the head reaches a certain point in its travel, and a weight 100 connected to said head and adapted to move said head away from said support when the circuit through the motor is opened.

5. In an artificial flower press, a die support and a presser head, an electric motor for moving said head toward said support, means for automatically opening the circuit through the motor when the head reaches a certain point in its travel, independent means for returning said head to its starting point upon opening of the circuit, and means actuated by the return movement of the head for closing the circuit at the point where it was opened.

6. In an artificial flower press, a die support and a presser head, an electric motor for moving said head toward said support, and means for automatically opening the circuit through the motor when the head reaches a certain point in its travel, said means including a pair of co-operating parts one of which is mounted on the said head.

7. In an artificial flower press, a die support and a presser head, an arched frame extending above said die support, a vertical 125 rack bar guided upon said arched frame and having the presser head upon its lower end, a pinion meshing with said rack bar, an electric motor operatively connected to said pinion, and means whereby the electric cir- 130

cuit through the motor is automatically broken when the rack bar has moved a certain distance.

8. In an artificial flower press, a die support and a presser head, power mechanism including an electric motor for said presser head, and a pair of contact members adjacent the said support and adapted to be joined to close the electric circuit through 10 the said motor by the positioning of a die on the said support including a pair of con-

tact members, and a part carried by the rack bar and adapted to separate said contact members.

In testimony whereof I have signed my 15 name to this specification, in the presence of two subscribing witnesses, this 15th day of January, 1917.

SAMUEL THOMAS WALKUP.
